UNITED STATES PATENT OFFICE.

JOSEPH S. OECHSLE, OF PHILADELPHIA, PENNSYLVANIA, ASSIGNOR TO METALWELD SERVICE CORPORATION, OF PHILADELPHIA, PENNSYLVANIA, A CORPORATION OF PENNSYLVANIA.

ATTACHMENT FRAME FOR MOBILE UNITS.

Application filed August 28, 1925. Serial No. 52,562.

REISSUED

This invention relates generally to mobile units, that is to say, units adapted to some useful purpose while capable of propulsion under their own power from place to place, in contradistinction to those now commonly known as portable units, or which involve trailing from one sphere of operation to another. Units of the character first mentioned are of diversified types, but usually embody some utility and a source of propulsive power, said utility being operated by the source of power when the latter is disconnected or not engaged in transportation.

An object of this invention is to provide an attachment frame for rigid connection to a motive unit—such as a tractor for example—which is so designed as to ensure a non-vibratory support for the utility adapted for operation by the motive unit when not engaged in propulsion or travelling from place to place.

Another object of this invention is the provision of an attachment frame component characterized by great strength and ease of connection or disconnection to the crank case and rear axle housings of standard types of tractors whereby said tractors are adapted to include a work utility or the like and operate the same with maximum economy.

A further object of this invention is the cheap and economical conversion of standard tractors into mobile units including one or more utilities adapted for operation thereby.

With the foregoing and other objects in view, which will be apparent from the following description, this invention essentially consists of the matters hereinafter set forth, typically exemplified in the accompanying sheets of drawings, and circumscribed as to subject-matter and scope by the appended claims.

In the drawings:

Figure 1—is a top plan view of my novel attachment frame as adapted to a standard type of tractor, a portion whereof is fragmentarily shown, while the associated utility is indicated diagrammatically by dot-and-dash outline so as not to confuse the illustration.

Figure II—is a side elevation of the preceding figure.

Figure III—is a perspective view of the attachment frame with minor parts broken away for the sake of clearness; and,

Figure IV—is a fragmentary detail of a portion of the attachment frame, later on fully explained.

For the sake of practical explanation as to one convenient application of the present invention I have elected—by way of example only—to describe the same as adapted to a mobile compressor unit, but it is to be distinctly understood that I am in no sense limited thereby.

Referring more specifically to the drawings, on which like reference numerals are applied to corresponding parts in all the views, it will be observed that the rear portion of a standard type of tractor is comprehensively designated 5, while the numeral 6 indicates the rear axle housings. 7 is the steering wheel, 8 the operator's seat, 9 the foot brake, 10 the gear shift, 11 the clutch control, and 12 the lever which connects or disconnects the compressor 13, as later on explained. The rear wheels of the tractor 5, are designated 14 while a portion of the fuel tank is shown at 15. As the foregoing parts are old and well known, further explanation thereof is deemed unnecessary herein, and they are but briefly enumerated as essential to a full comprehension of my invention, now to be described in detail.

As best appreciated from Figure III, it will be noted that, in the main, this invention comprises a framework attachment, comprehensively designated 16, and comprising opposed side units 17, 18, detachably connected at their rear ends by a transverse member 19. Each side unit 17, 18, it will be seen, consists, conveniently though not essentially, of a standard I-beam or longitudinal 20, that is cut away and shaped as later on fully explained, with a sub-plate 21 welded to the fore basal flanges thereof at 22, as well as rigidly united by spot weldings 23, through said basal flanges at each side of the web thereof. These sub-plates 21, it is to be particularly remarked, thus become incorporated base flanges of the I-beams 20 and they are configured to snugly conform to the crank case 24 of the tractor 5. In addition to the foregoing, the sub-plates

21 are provided with a series of holes 25 adjacent their inner edges for substitute bolts 26—Figure I—which pass through the ordinary flange holes of the crank case and 5 cover, as will be well understood by anyone acquainted with tractors. Furthermore, the type of tractor illustrated, is provided on the rear axle housings 6 with vertical offsets 27—Figure II—and these I bore and tap to 10 receive studs 28 passed through holes 29—Figure III—in the aforesaid sub-plates 21. Thus it will be seen that the side units 17, 18 are rigidly supported and connected to the tractor 5 in a manner effectively precluding 15 any tendency to lateral or other displacement while affording rearwardly extending stable support for the compressor 13.

In order to rigidly brace the side units 17, 18 against vertical deflection, I weld obliquely 20 disposed angles or channels 30 to the lower rear flanges of the I-beams 20 at 31; said angles or channels 30 being cut away and shaped at their forward ends to provide eye-pieces 32 which are bolted or otherwise secured at 33 to the flange of the juxtaposed axle housing 6, as clearly shown 25 in Figure II. Attention is also directed to the fact that I additionally unite the brace members 30 rigidly to the base flanges of the 30 I-beams 20 by spot weldings 34—Figure III.

Referring now to the rear transverse member 19, the same is conveniently cut from a standard channel section to snugly seat at 35—Figure III—between the upper and 35 lower flanges of the I-beams 20, and it has angle clips 36—Figure IV—welded thereto by means of which it is secured in place between the side units 17, 18 through the medium of bolts 37. Thus it will be readily 40 seen that the side units 17, 18 are transversely braced in a rigid manner at their rear ends, and thereby afford a secure bearing for the compressor 13 which is mounted thereon and secured in place by bolts 38—45 Figure II—passing through holes 39 in the top flanges of the I-beams 20—Figure III. Obviously additional transverse channels may be fitted at intervals intermediate the side units 17, 18 where deemed necessary.

50 As the specific form of unit illustrated involves a storage tank 40 for the compressed air produced by the compressor 13, I afford chock spacers therefor in the form of transversely disposed angle irons 41, 42 of sufficient length. These angle irons 41, 42, it will be seen, extend beyond the side lines of the attachment frame 16, and the former 41 is integrally welded at 43 to the top flange of the transverse member 19, while the latter 55 has angle clip 44 welded thereto with provision for bolting connection 45 to the aforesaid I-beams 20, as will be readily understood. The storage tank is secured to the chock spacers 41, 42 by removable straps 46 60 and bolts 47, in the well known manner.

From the foregoing it will be seen that the attachment frame 16 extends rearwardly from the tractor 5, and that it forms and constitutes a rigid support for the compressor 13 which is operated by a direct 70 drive connecting shaft 48—Figure II—from the tractor transmission, and that it can be connected or disconnected from operation therefrom by the lever 12, aforesaid.

From the foregoing description, taken in 75 connection with the accompanying drawings, the construction and manner of mounting or dismantling my novel attachment frame will be well understood without further detailed explanation, while its ready adaptability for compact shipment is self evident. Furthermore, changes in the form, proportions and minor details, obviously, may be made within the scope of my invention without departing from the spirit or sacrificing 80 any of the advantages thereof, particularly in so far as the cutting away of the I-beam 20—flanges is concerned to conform to different types of prime movers, as well as to accommodate other utilities than that specifically illustrated. Accordingly the right is hereby reserved to make all such reasonable changes as are fairly circumscribed by the scope of the subjoined claims.

Having described my invention what I 90 claim as new and desire to secure by Letters Patent is:

1. An attachment frame of the type described comprising spaced I-beams having their forward lower flanges reinforced by co-planar sub-plates with the rear ends transversely connected by a detachable standard section, and obliquely disposed bracing members rigidly secured to the rear lower flanges of said I-beams.

2. An attachment frame of the type described comprising spaced I-beams having their forward lower flanges reinforced by abutting sub-plates with the rear ends transversely connected by a detachable standard section, and obliquely disposed standard section bracings integrally welded to the rear lower flanges of the I-beams.

3. An attachment frame of the type described comprising spaced I-beams having their forward ends reinforced by sub-plates integrally welded in planar abutment on the lower flanges thereof, a transverse channel detachably connecting the rear ends of said I-beams, and obliquely disposed standard section bracing members integrally secured to the rear lower flanges of said I-beams.

4. An attachment frame of the type described comprising spaced I-beams having their forward ends reinforced by sub-plates integrally united to the lower flanges thereof, said plates being configured to fit and be attachable to the crank case flanges of a standard tractor, a transverse channel-member detachably connecting the rear ends of

the aforesaid I-beams, and obliquely disposed bracing members integrally attached to the rear lower flanges of said I-beams.

5. An attachment frame of the type described comprising spaced I-beams having at their forward ends sub-plates integrally united to the lower flanges thereof, said I-beams and sub-plates being respectively shaped to mount a work unit and configured for attachment to the crank-case of a standard tractor, a transverse channel-member detachably connecting the rear ends of the I-beams, and obliquely disposed bracing members integrally attached to the rear lower flanges of said I-beams.

6. An attachment frame of the type described comprising spaced I-beams having at their forward ends sub-plates integrally united to the lower flanges thereof, said I-beams and sub-plates being respectively shaped to mount a work unit and configured for attachment to the crank-case of a standard tractor, a transverse channel-member having its ends shaped to engage between the flanges of—and be detachably connected to—the rear end webs of the I-beams, and obliquely disposed standard-section bracings integrally united to the rear lower flanges of said I-beams with their free ends cut away and apertured to constitute eye-pieces for connection to the tractor rear axle housings.

7. An attachment frame of the type described comprising spaced I-beams having sub-plates integrally united to the lower flanges at one end thereof, said I-beams and sub-plates being respectively shaped to mount and conform with a work unit and co-ordinated tractor, a transverse channel-member having an inverted angle section chock welded longitudinally of its upper flange and similarly connected clips integral with the web whereby the rear ends of the I-beams are detachably connected, and obliquely disposed standard-section braces integrally united to the rear lower flanges of said I-

beams with their free ends affording eye-pieces for attachment to the tractor rear axle housings.

8. An attachment frame of the type described comprising spaced I-beams having sub-plates integrally united to the lower flanges at one end thereof, said I-beams and sub-plates being respectively shaped to mount and conform with a work unit and co-ordinated tractor, a transverse channel-member having an inverted angle section chock welded longitudinally of its upper flange and similarly connected clips integral with the web whereby the rear ends of the I-beams are detachably connected, a second angle-section chock having integral clips whereby it is secured transversely of the attachment frame, and obliquely disposed standard-section braces integrally united to the rear lower flanges of said I-beams with their free ends affording eye-pieces for attachment to the tractor rear axle housings.

9. As a unit for attachment frames of the type described, an I-beam having a sub-plate integrally secured co-planar to the lower flange at one end thereof, and an obliquely disposed standard-section brace similarly united to the rear lower flange at the other end with the free end thereof fashioned into eye-piece formation.

10. As a unit for attachment frames of the type described, an I-beam having a sub-plate integrally secured co-planar to the lower flange at one end thereof, and an obliquely disposed standard-section brace similarly united to the rear lower flange at the other end with the free end thereof fashioned into eye-piece formation, the aforesaid I-beam and sub-plate having their longitudinal edges shaped and configured for the purposes hereinbefore set forth.

In testimony whereof I affix my signature the eighteenth day of July, 1925.

JOSEPH S. OECHSLE.
